FISHING LURE

Paul R. Staley, Fort Wayne, Ind.

Application October 8, 1956, Serial No. 43,255

Term of patent 14 years

(Cl. D31—4)

I claim:

The ornamental design for a fishing lure, substantially as shown.
